HANGER FOR ELECTRIC FIXTURES

Abraham Owen Monson, Long Beach, Calif.

Application August 30, 1952, Serial No. 307,237

1 Claim. (Cl. 248—216)

This invention relates to a hanger or support for fixtures such as outlet and junction boxes in installations of electric wiring.

An object of the invention is to provide a hanger which does not have to be bridged between two supporting structural members but which may be securely fastened to a single wall-stud, floor or ceiling joist or similar part of the building or like structure.

A further object of the invention is to provide a hanger which may be accurately placed in position to support an outlet or junction box in definite, predetermined relationship to a wall, floor or ceiling surface.

Still another object is to provide means for securing an outlet or junction box to a supporting hanger which permit selection of the placement of the tightening means used therewith, so as to be adapted to a variety of types of boxes and conditions of use.

As will be apparent from the foregoing and will appear more specifically as the following description proceeds, it is a general object of the invention to provide a hanger of great simplicity and low cost of manufacture and of like simplicity and low cost of installation.

In the accompanying drawing, illustrative of a presently preferred embodiment of my invention.

Fig. 1 is a perspective view;

Fig. 2 shows the hanger attached to a structural member, such as a ceiling joist;

Fig. 3 is a sectional exploded view of the means for attaching a box to the hanger, on the line of section 3—3 of Fig. 2; and

Fig. 4 is sectional view of the hanger on the line 4—4 of Fig. 2 but showing the hanger attached to a structural member such as a wall-stud.

Having reference now to the details of the drawing, my hanger comprises a strap 6, of steel or other suitable material bent in U-form to have two parallel arms, forming a narrow and short channel. The arms may be spaced only far enough apart to permit a fitting 7 to be moved slidably along one of them. One arm 8 terminates in a sharpened point 9, which at its base may be about half of the width of the strap 6 so as to leave a shoulder 10. The other arm 11 terminates in an ear 12, bent outwardly away, from the arm 8 at a right angle so as to have that face 13 of the ear 12 nearest the point 9 in alignment with the shoulder 10.

The point 9 extends sufficiently beyond the plane of the face 13 to act as a holding spike when driven into building material to the shoulder 10. The ear 12 has a hole 14 to receive a nail 15 or other suitable fastening. The arm 8 has a series of gauge marks 16, 17, 18 and so forth, spaced at intervals measured from the point 9. These marks may of course be calibrations in linear measure, such as inches, but as the sizes and shapes of outlet boxes now generally conform to underwriters' standards which specify boxes of three definite depths, the gauge marks may conveniently be spaced from the point 9 at distances correlated to the box depths. That is, when the hanger is installed as hereinafter described with the arm 8 at a gauged distance from the outer face of a stud or joist and parallel to that face, a box correlated in depth to the particular gauged distance will be supported by the arm 8 so as to have its open side slightly outwardly of the face of the stud or joist, allowance being made for finishing surface material. The mark 18, nearest the point 9, is spaced from the point 9 at a distance equal to the depth of the shallowest box, less an allowance for wall finish, and the marks 17 and 16 are

2

spaced from the mark 18 at distances equal to the additional depth of the boxes to which they correspond.

The fitting 7 is a nipple with exterior threads 20 to receive a nut 21, and has two opposed circumferential slots 22 and 23 of sufficient size to receive the arm 8 slidably. The nipple 7 is intended to be inserted through one of the usual wall holes of an outlet box (not shown) and the nut 21 may then be tightened against the inner side of the box wall to clamp the box to the arm 8 at any selected position along the arm 8. The nipple 7 also has interior threads 24 to receive a threaded lug or stud with which some types of box are provided.

The method of installing the hanger upon a structural member 25 so that the arm 8 will be parallel to the face 26 of the member 25 and at a distance inwardly from the face 26 correlated to the size of the box which the hanger is to support, will now be described. If it be supposed that the structural member 25 in Fig. 2 is a ceiling joist to which a ceiling outlet is to be attached, the face 26 will be the bottom edge of the joist and the face 27 will be a vertical side of the joist. The hanger is held with the flat outer side of the arm 8 against the face 27, with the point 9 extending upwardly, and is advanced upwardly until the appropriate gauge mark, say the mark 18 for a shallow box, is at the face 26. The U-end of the hanger is then swung upwardly, pivoting on the point 9, until the arm 8 is horizontal, and the point 9 is driven into the joist up to the shoulder 10 by hammering on the bight 31 of the U-bend of the hanger. As the straight arm 8 will transmit the full force of a blow on the bight 31 to the point 9, a single hammer blow will usually suffice, and the hanger becomes accurately positioned in its measured position with only the time and effort required for a gauged placement, a pivot, and a blow. The ear 12 will then lie against the face 27, and may be secured thereto by a nail 15 driven through the hole 14. The alignment of the bearing face 13 of the ear 12 with the shoulder 10, assures horizontality of the arm 8.

The method of attaching a hanger to a wall-stud 28 will be obvious from the foregoing, the face 29 of the member 28 being the outer edge of the stud. As shown in Fig. 4, a box would be secured to the nipple 7 by its upper or lower wall instead of its rear wall. To secure a box by the rear wall, the hanger would be held against the wall-stud 28 with the flat side of the arm 8 against the side face 30 of the stud.

To install the hanger for boxes of greater depths than the minimum, the gauge mark 16 or 17 is used, as may be appropriate to the box size.

The outlet or junction box need not be placed on the nipple 7 until after the hanger is installed. When the box has been placed upon the nipple, the nipple is moved along the arm 8 to a desired position and the nut 21 is placed upon the nipple and tightened, clamping the box wall through which the nipple extends against the arm 8, and thus clamping the nipple in fixed position upon the arm. If the box has a stud to be engaged in the interior threads 24, the stud may reach the portion of the arm 8 within the nipple 7 and clamp the nipple to the arm, but with a short stud this may not occur, and it may be difficult to get at the nut 21 between the arm 8 and the back wall of the box. Therefore the exterior threads 20 preferably extend to both ends of the nipple 7 and the slots 22 and 23 are spaced from each end of the nipple to leave whole threads at each end. Thus when a box with a short stud is secured by the interior threads 24 the nut 21 may be placed on the threaded end of the nipple between the arms 8 and 11 and will equally well clamp the nipple to the arm 8.

I claim:

A hanger for electric fixtures comprising: two parallel arms joined at one end to provide a striking point adapted to receive a hammer blow; an attaching ear on the other end of one of said arms at a right angle to both of said arms and on the side of said one arm opposite to the other of said arms; a shoulder on the other of said arms in alignment with the attaching face of said ear; a point on said other arm beginning at said shoulder and in lengthwise extension of said other arm; means for locating said other arm at varying fixed distances from the face of a wall comprising gauge markings on said other arm de-

2,699,311

3

fining distances from the end of said point; and means for supporting a fixture slidable on said other arm and adapted to be secured thereto.
